UNITED STATES PATENT OFFICE.

JOHN GATELY, OF GRETNA, NEBRASKA.

GRAIN-SEPARATOR.

1,124,128.

Specification of Letters Patent.

Patented Jan. 5, 1915.

Application filed June 23, 1914. Serial No. 846,885.

To all whom it may concern:

Be it known that I, JOHN GATELY, a citizen of the United States, residing at Gretna, in the county of Sarpy and State of Nebraska, have invented new and useful Improvements in Grain-Separators, of which the following is a specification.

The invention provides a rack intended chiefly for separating grain, said rack embodying sets of toothed bars which are connected in series and arranged to have a reciprocatory movement imparted thereto, the purpose being to provide a separating surface which will effectively support straw, cobs and the like, while at the same time affording a ready escape for the detached kernels of grain.

The invention consists of toothed bars and fluted strips at the sides of such bars, such strips being arranged in the spaces formed between the bars and having crimps which serve to direct the grain downward and to urge the straw and cobs forward to the tailings or delivery end of the separating surface.

The invention consists of the novel features, details of construction and combination of parts, which hereinafter will be more particularly set forth, illustrated and claimed.

In the drawings hereto attached:—Figure 1 is a top plan view of a grain separator embodying the invention. Fig. 2 is a longitudinal section. Fig. 3 is a cross section on the line $\alpha-\alpha$ of Fig. 1, looking in the direction of the arrows. Fig. 4 is a cross section on the line $\gamma-\gamma$ of Fig. 1, looking in the direction of the arrows. Fig. 5 is a detail perspective view of a portion of one of the toothed bars and fluted and crimped strip coöperating therewith. Fig. 6 is a detail view of a portion of one of the fluted and crimped strips.

Corresponding and like parts are referred to in the following description, and indicated in all the views of the drawings, by the same reference characters.

The numeral 1 designates generally a main frame for supporting the working parts.

Side pieces 2 project upward from the main frame and prevent lateral displacement of the grain passing through the machine and over the separating surface.

A crank shaft 3 is located at one end of the frame and a second shaft 4 is mounted

in the frame near the crank shaft and is provided near opposite ends with bars 5 which project and form opposed arms.

The separating surface is formed of a plurality of toothed bars 6 which are arranged side by side between the side pieces 2 and spaced apart a comparatively short distance. The bars 6 are of like formation, the upper edges thereof being provided with teeth and their sides being straight. The toothed bars are arranged in two sets, the bars of each of the sets being connected for simultaneous movement and the bars of one set alternating with the bars of the other set, the two sets of bars receiving a simultaneous movement in opposite directions so that while the bars of one set are returning, the bars of the other set are advancing.

Cross pieces 7 connect the front ends of the bars of the several sets and other cross pieces 8 connect the toothed bars near their rear ends, the cross pieces 8 projecting beyond the side pieces 2 and receiving the lower ends of hangers 9 which support the bars in a manner to admit of their receiving a reciprocating movement. Links 10 connect one set of toothed bars with the upper arms of the bars 5 and other links 11 connect the other set of toothed bars with the lower arms of the bars 5. A rocking movement of the shaft 4 results in an opposite reciprocating movement of the two sets of toothed bars.

Links 12 connect the crank portions of the crank shaft 3 with the bars 5. Rotary movement is imparted to the crank shaft in any convenient manner and results in a rocking movement of the shaft 4. The two sets of bars in addition to their reciprocating movement also have a vertical movement imparted thereto with the result that the straw, cobs or the like is elevated and at the same time advanced, the movement being gradual and step by step, with the result that the grain is loosened and ample opportunity afforded for the escape of the same, such grain passing through the spaces formed between the toothed bars whereas the straw, cobs and the like is carried over the end of the surface and discharged in the well known manner.

A metal strip 13 extends along one side of each of the toothed bars and is arranged in the space formed between proximal sides of adjacent toothed bars. The metal strips

13 are fluted thereby forming vertical spaces 14 which insure a positive escape for the grain. The outer surfaces of the parts of the strips 13 arranged between the vertical spaces 14 are formed with crimps 15, such crimps being inclined and the crimps upon opposite sides of each of the vertical spaces 14 being oppositely inclined with the result that they assist materially in the separation and discharge of the grain and in the forward movement of the straw, cobs and the like. Each of the toothed bars is provided with a metal strip 13 and such strips are arranged upon the sides of the toothed bars facing in the same direction. The strips 13 are spaced from the sides of the bars between which they are arranged except at the points of attachment thereto and as a result a separating surface is provided which insures a maximum delivery of the straw, cobs and like material while at the same time providing ample escape for the grain. The tendency of the strips 13 to spring laterally prevent any possible choking or binding of the grain in the vertical spaces or discharge outlets 14.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the invention as claimed.

Having thus described the invention, what is claimed as new is:—

1. A separating surface for grain, the same comprising a plurality of spaced bars, means for imparting a reciprocating movement thereto, and strips arranged in the spaces formed between the bars and crimped throughout their length to provide a plurality of grain outlets.

2. A separating surface for grain comprising a plurality of spaced bars, means

for imparting a reciprocating movement thereto and strips arranged between the bars and formed throughout their length with flutes forming a plurality of grain outlets and having the portions between the flutes formed with crimps. 55

3. A separating surface for grain comprising a plurality of spaced bars, means for imparting a reciprocating movement 60 thereto and strips arranged between the bars and formed throughout their length with flutes forming a plurality of grain outlets and having the portions between the flutes formed with crimps, the crimps upon opposite sides of the flutes being reversely inclined. 65

4. A separating surface for grain, the same comprising a plurality of spaced bars, and fluted strips arranged in the spaces 70 formed between the bars and spaced from the sides of the bars to admit of a lateral yielding to prevent choking or binding of the grain in the outlets formed by the flutes. 75

5. A grain separating surface comprising two sets of toothed bars arranged to receive an opposite reciprocating movement, the bars of one set alternating with the bars of the other set and fluted strips attached to the sides of the bars facing in the same direction, such fluted strips being arranged between adjacent bars. 80

6. A grain separating surface comprising two sets of toothed bars arranged to receive an opposite reciprocating movement, the 85 bars of one set alternating with the bars of the other set and fluted strips attached to the sides of the bars facing in the same direction, such fluted strips being arranged between adjacent bars and having the portions 90 between the flutes oppositely crimped, said strips being spaced from the bars to yield laterally and prevent choking or binding of the grain in the outlets formed between adjacent toothed bars. 95

In testimony whereof I affix my signature in presence of two witnesses.

JOHN GATELY.
